(57) **CLAIM**

The ornamental design for a panel for kimchi refrigerator, as shown and described.

DESCRIPTION

FIG. 1 is a perspective view of a panel for kimchi refrigerator showing the claimed design;

FIG. 2 is a front view showing the claimed design;

FIG. 3 is a rear view showing the claimed design;

FIG. 4 is an enlarged left side view showing the claimed design;

FIG. 5 is an enlarged right side view showing the claimed design;

FIG. 6 is an enlarged top plan view showing the claimed design; and,

FIG. 7 is an enlarged bottom plan view showing the claimed design.
